CLAIM

The ornamental design for a transport structure, as shown and described.

DESCRIPTION

FIG. 1 is a perspective view of the transport structure showing our new design;

FIG. 2 is a front elevational view of the transport structure, the rear elevational view being a mirror image thereof;

FIG. 3 is a left side elevational view of the transport structure, the right side elevational view being a mirror image thereof;

FIG. 4 is a top plan view of the transport structure; and,

FIG. 5 is a bottom plan view of the transport structure.
